his Attorney.

UNITED STATES PATENT OFFICE.

FRIDRICH W. RAHN, OF CHICAGO, ILLINOIS.

COLLAPSIBLE BED-BOLSTER.

1,139,719.

Specification of Letters Patent. Patented May 18, 1915.

Application filed February 20, 1914. Serial No. 819,918.

To all whom it may concern:

Be it known that I, FRIDRICH W. RAHN, a citizen of the United States, and a resident of the city of Chicago, county of Cook, and State of Illinois, have invented certain new and useful Improvements in Collapsible Bed-Bolsters, of which the following is a specification.

My invention relates to improvements in bed bolsters and has for its object the provision of an improved device of this character provided with improved means for stretching and folding the same and also provided with improved means for securing the parts together, the present invention constituting an improvement over my prior invention as set forth in Patent No. 1,082,171, dated December 23, 1913.

The invention consists in the combinations and arrangements of parts hereinafter described and claimed.

The invention will be best understood by reference to the accompanying drawing forming a part of this specification, and in which,

Figure 1 is a perspective view, with portions broken away, of a bed bolster embodying my present invention, Fig. 2, a section taken substantially on the plane of the line $\alpha-\alpha$ of Fig. 1, Fig. 3, a section taken on the plane of line $y-y$ of Fig. 2, Fig. 4, a perspective view of a metallic ring employed in the construction, and Fig. 5, a section taken on line $z-z$ of Fig. 1.

The preferred form of construction as illustrated in the drawing comprises two sheet metal disks 1 arranged at the ends of a flexible member 2 of canvas or other suitable fabric and having its ends 3 folded inwardly over end members 1, said flexible member being arranged in substantially cylindrical form with a longitudinal opening at one side adapted to permit of the insertion of articles therein. The ends 3 are se-

cured in place by means of tangs 4 formed on the edges of metallic rings 5 which are also provided with tangs 6 at their inner edges, said tangs 6 being inserted through a central opening in the corresponding disk 1 and clenched over the inner faces thereof as shown in Fig. 3. Suitable ornamental caps 7 are arranged over disks 5 to protect the same and present an ornamental appearance. This constitutes a simple and effective means for securing the ends of the flexible member 2.

Longitudinal stretcher bars 8 are arranged at the edges of the opening in flexible member 2 and a foldable stretcher member 9 is placed intermediate members 8 in the bottom of the receptacle. Each of the stretcher members is provided at one end with a head 10 adapted to abut the inner face of the corresponding end member 1 and are provided with projections 11 adapted to fit within segmental slots 12 in the corresponding end member. Stretcher member 9 is provided with a hinge 13 by means of which the same may be folded and which thus facilitates insertion and removal thereof. At their other ends each of the stretcher members is provided with a threaded extension or head member 14 provided with a head flange 15 taking against the face of the corresponding disk 1 and with a projection 17 taking into corresponding openings in the corresponding end disk 1. Each of the heads 14 is provided with a square opening 17 in its end and a key 18 is provided to fit said openings and thus serve as a means of turning the heads 14 on the corresponding stretcher members and thus stretching flexible member 2 as will be readily understood.

Arms 19 are slidably mounted on the inner faces of disks 1 and are connected at their inner ends with oppositely disposed crank pins 20 on a rotatable disk 21. Each of the disks 21 is operated by means of an arm 22 having a perforation 23 therein adapted to fit over a stud 24 secured to the inner face of the corresponding disk 1 and by means of which the corresponding disk 21 will be locked in central position as indicated in Figs. 1 and 2. Arms 19 are provided with notches at their outer ends adapted to receive the corresponding stretcher members 8 and lips 25 are provided on the inner faces of the disks 1 and adapted to engage the heads on the corresponding stretcher members 8 as said stretcher members are drawn together by the operation of the lever arm 22. By this arrangement it will be observed that the flexible member 2 may be stretched laterally and at the same time the stretcher members automatically locked against displacement. A swinging brace 26 is arranged centrally in the receptacle and has its ends hingedly connected with the stretcher members 8 and serves as a means for holding the central portion of the receptacle in distended form as will be readily understood.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of 10 the appended claims.

Having described my invention what I claim as new and desire to secure by Letters Patent is:

1. A device of the class described comprising two end members; a flexible member secured to said end members to form a receptacle open at one side; stretcher members attached to said flexible member at the edges of said opening and bearing against the inner face of one of said members; extensible heads threaded to the other ends of said stretcher members and provided with key holes in their ends, there being corresponding openings in the abutting end member; and shoulders on said heads engaging against the inner sides of said end members, substantially as described.

2. A device of the class described comprising two end members; a flexible member se-

cured to said end members to form a receptacle open at one side; stretcher members attached to said flexible member at the edges of said opening and bearing against the inner face of one of said members; extensible heads threaded to the other ends of said 35 stretcher members and provided with key holes in their ends, there being corresponding openings in the abutting end member and said heads extending into said openings; and stop flanges on said heads abutting the end member, substantially as described.

3. A device of the class described comprising two centrally perforated end members; a flexible head having its ends folded in 45 over said end members; and metal rings having tangs at their outer edges clenched through said folded ends and tangs at their inner edges clenched through the perforation in said end members, substantially as 50 described.

In testimony whereof I have signed my name to this specification in the presence of two subscribing witnesses.

FRIDRICH W. RAHN.
